CLAIM

The ornamental design for a transport wheelchair single use disposable cover, as shown and described.

DESCRIPTION

FIG. 1 is a perspective view of a disposable single use cover in place, having the arm rest cover in the second position; showing my new design in use.

FIG. 2 is a flat view thereof; with the arm rest covers still having the perforations in place, and in the first position, and the leg covers.

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is another perspective view thereof; with the disposable cover in place with the right leg support cover in place, the left leg cover support would be a mirror image. Also having the arm rest covers in the second position; and,

FIG. 10 is an exploded view thereof; with the transport wheelchair having the right and left arm rest in the first position upwardly, and the disposable single use cover in place.

The broken lines shown of the whole transport wheelchair and the seat of the cover is included for the purpose of illustrating environment and form no part of the claimed design.
